HAIR CURLER

Costas N. Laskaris, New York, N. Y.

Application November 8, 1940, Serial No. 364,804

6 Claims. (Cl. 132—40)

This invention relates to hair curlers and has particular reference to a curler upon which a lock of the hair is wound into a tight spiral and maintained in said tightly wound condition until set and which may be arranged with the axis thereof disposed either parallel or perpendicular to the head.

The invention primarily comprehends a curler for producing tight curls close to the head and which may be freed from the curler without disturbing or unwinding the curl.

The invention further comprehends a curler of the spool type consisting of interfitting sections which are separable to permit of the withdrawal of the curler from the curl without disturbing or unwinding the same and which curler is provided with a spring clip rotatable circumferentially thereof and swingable into overlying clamping relation with the end of the curled lock adjacent the head for holding the curl in tightly wound condition until the same is set.

More specifically the invention resides in a spool-shaped core upon which the hair is wound and confined between the flanges thereof, one of the flanges being separable to facilitate the removal of the curler from the hair without disturbing or unwinding the curl, the opposite flange rotatably mounting a spring clip circumferentially movable about the spool and pivoted for swinging movement for attachment with the opposite flange and into clamping engagement with the curl for securing the same thereon.

The invention further embodies a curler of the aforesaid character which is efficient for its intended purpose, which may be manufactured at a minimum cost and which is easily applied to the hair to produce a tightly wound curl and readily removable therefrom.

With the foregoing and other objects in view, reference is now made to the following specification and accompanying drawing in which there is illustrated the preferred form of the invention.

In the drawing:

Fig. 1 is a view illustrating several of the hair curlers in applied position, certain of the same having the axes thereof parallel to the head and one with the axis thereof perpendicular thereto.

Fig. 2 is an enlarged perspective view of the curler illustrating the sections in separated juxtaposition.

Fig. 3 is an enlarged longitudinal sectional view.

Fig. 4 is an end view thereof.

Fig. 5 is a transverse sectional view on the line 5—5 of Fig. 3.

Referring to the drawing by characters of reference, the curler includes a tubular or preferably cylindrical hollow core 10 having spaced perforations 11 and provided with a peripheral flange 12 secured thereto at one end thereof and formed with a reduced exteriorly threaded boss 13 at the opposite end thereof for receiving thereover the interiorly threaded hub 14 of an oppositely disposed peripheral flange 15.

10 As illustrated, the core 10 and the hub 14 are formed at the outer ends thereof with a plurality of outwardly projecting fingers 16 which engage through radially arranged slots 17 disposed circumferentially of inwardly offset central bosses 18 secured within the outer ends of the core 10 and hub 14 respectively by the rebending of the free ends of the tongues into impinging relation with the outer face of the said inwardly offset bosses. The flange 12 has its marginal edge 19 turned to provide an inwardly opening annular channel 20 in which channel is rotatably mounted a disk 21. A spring clamp 22 having its medial portion inwardly bowed is pivoted at one end thereof as at 23 to the disk 21 and at the opposite end thereof is formed with a hooked terminal 24 for latching engagement with the beaded outer edge 25 of the flange 15. The clamp 22 is pivoted to the disk 21 for swinging movement from an open relation, as shown in Fig. 2, to a closed relation as shown in Fig. 3, with the inwardly bowed portion thereof disposed adjacent to the core 10 and tensioned against outward movement.

Under this construction and arrangement the clamp 22 is thereby associated with the core to permit of its circumferential adjustment around the same to any desired position to coincide with the end of the curled lock adjacent the head for holding the curl in wound condition upon the core. The clamp 22 is further formed with an enlarged outwardly bowed portion 26 adjacent its pivotal connection which spaces the same from the flange 12 and which tensions the hooked terminal 24 into latching engagement with the beaded edge 25 and permits of the resilient longitudinal movement of the clamp to facilitate the unlatching thereof.

In order to anchor the end of a lock of hair to the core 10 for winding the same thereon, the core is provided with a semi-cylindrical perforated clip 27 which is pivoted thereto on a transverse pin 28 adjacent the flange 12 for swinging movement from an open relation as shown in Fig. 2, into overlying longitudinal relation with the core.

55 The curler is adapted to produce tight curls by

anchoring the end of a lock of hair between the core and the clip 27 and spirally winding the entire length of the lock of hair around the core until the flanges of the curler engage with the head after which the clamp 22 is adjusted circumferentially of the curl and latched into closed relation with the inwardly bowed portion thereof resiliently clamping the curled lock at the ends of the hair adjacent the head. The curl is retained on the curler a sufficient length of time to permit the same to become set so as to retain the curled formation when displaced from the curler.

The curler is removed by first loosening the spring clamp 22, removing the flange 15 from the core 10 and then axially withdrawing the core from the curl thus obviating the necessity of unwinding the curl to effect the removal of the curler therefrom.

The core 10 being of hollow construction, permits of the circulation of air through the perforations therein and those in the clip 27 to the convolutions of the curl to facilitate a more rapid drying and setting of the curl.

What is claimed is:

1. In a hair curler, a tubular core upon which the hair is adapted to be wound, a clip pivoted to said core adjacent one end thereof for securing the ends of the hair between the clip and core, a peripheral flange fixed to the core at one end thereof and having its peripheral edge inturned, a peripheral flange telescopically fitting over the opposite end of the core and removable therefrom for withdrawing the core axially from the curl and having a beaded peripheral edge, a member rotatably mounted between said first named flange and the inturned peripheral edge thereof, and a spring clamp pivoted at one end to said rotatably mounted member and having latching engagement with the beaded edge of the opposite flange and rotatable circumferentially of the core for clamping engagement with the curl adjacent the head.

2. In a hair curler, a core upon which the hair is adapted to be wound, means on said core for anchoring the free end of the hair thereto, a peripheral flange fixed to the core at one end thereof and having an inwardly directed marginal edge providing an inwardly opening annular channel, a peripheral flange removably associated with the opposite end of the core for permitting of the axial withdrawal of the core from the curl, a member rotatably mounted in the annular channel of said first named flange and an inwardly bowed spring clamp pivoted at one end to said rotatably mounted member and having means for detachable latching engagement with the opposite flange for retaining the hair in coiled formation on the core and for releasably securing the detachable flange in associated relation with the core.

3. In a hair curler, a spool including a core upon which the hair is adapted to be wound, a peripheral flange fixed to the core at one end thereof, a peripheral flange removably associated with the opposite end of the core and adapted when removed from the core to permit of the axial withdrawal of the core from the curl, and an inwardly bowed spring clamp rotatably carried by the spool for movement circumferentially thereof and swingable into overlying clamping relation with the curl on the core and having means for detachable latching engagement with the removable flange.

4. In a hair curler, a core upon which the hair is adapted to be wound, a clip pivoted to said core adjacent one end thereof for securing the ends of the hair between the clip and core, said core having a reduced exteriorly threaded end, a peripheral flange having an interiorly threaded boss removably associated with said reduced threaded end of the core, a peripheral flange secured to the core at the opposite end thereof and having an inwardly directed marginal edge providing an inwardly opening annular channel, a member rotatably mounted in the said annular channel, and an inwardly bowed spring clamp pivoted at one end to said rotatably mounted member and having means for detachable latching engagement with the removable flange and rotatable and swingable by means of its connection with said rotatable member for disposing the same into overlying clamping relation with the curl on the core.

5. In a hair curler, a spool including a core upon which the hair is adapted to be wound, a peripheral flange fixed to the core at one end thereof, a peripheral flange removably associated with the opposite end of the core and adapted when removed from the core to permit of the axial withdrawal of the core from the curl and an inwardly bowed spring clamp extending longitudinally of the core and pivotally carried by the spool at one end thereof for swinging movement into overlying clamping relation with the curl on the core, and having means at the opposite end for detachable latching engagement with one of the flanges for releasably securing the removable flange to the core and for retaining the curl thereon.

6. In a hair curler, a spool including a core upon which the hair is adapted to be wound, peripheral flanges at the opposite ends of the core, an inwardly bowed spring clamp extending longitudinally of the core, means carried by the spool adjacent one end thereof rotatably and pivotally mounting the clamp for movement circumferentially of the core and to and from an overlying clamping relation with the curl on the core, and means for detachably latching the clamp with one of the flanges.
